CLAIM

The ornamental design for a smart flood light, as shown and described.

DESCRIPTION

FIG. 1 is a front, right, and top perspective view of a smart flood light, showing my design.

FIG. 2 is a rear, right, and bottom perspective view thereof.

FIG. 3 is a front elevation view thereof.

FIG. 4 is a rear elevation view thereof.

FIG. 5 is a left side elevation thereof.

FIG. 6 is a right side elevation thereof.

FIG. 7 is a top plan view thereof.

FIG. 8 is a bottom plan view thereof; and,

FIG. 9 is an enlarged view of a waterproof connector of the smart flood light labeled 9 in FIG. 2.

The dash-dash broken lines illustrate portions of the smart flood light that form no part of the claimed design. The dash-dot-dash broken lines indicate cutoff boundaries for the enlarged view and form no part of the claimed design.

1 Claim, 9 Drawing Sheets
